FIG.2.

UNITED STATES PATENT OFFICE.

CHARLES KUNKEL, OF ST. LOUIS, MISSOURI.

IMPROVEMENT IN ZITHERNS.

Specification forming part of Letters Patent No. **222,139**, dated December 2, 1879; application filed January 29, 1879.

To all whom it may concern:

Be it known that I, CHARLES KUNKEL, of the city of St. Louis and State of Missouri, have invented certain new and useful Improvements in Zitherns, thus constituting the seventeen-stringed "Kunkel's American Zithern;" and I do hereby declare that the following is a full, clear, and exact description of the invention, which will enable others skilled in the art to which it appertains to make and use the same, reference being had to the accompanying drawings, and to the letters of reference marked thereon, which form a part of this specification.

The object of my invention is to improve the zithern, a musical instrument somewhat similar to the guitar, which I accomplish, first, by the form which I give to the frame of the instrument; second, by giving such a form to the bridge or upper end of the instrument as to realize from the string arrangement the fullest possible advantages from an instrument of so limited compass as the zithern. I therefore arch the sounding-box so as to present a sufficient resistance to the strain of the strings of the instrument. I also facilitate the acquirement of practice on the instrument by attaching to the sounding-board the diatonic scale combined with frets, upon which a wedge-shaped block can be placed so as to affect the strings by full tones to insure correct tuning.

The tuning bridge-piece is shaped so as to afford to the strings of the first octave a greater length and consequent volume than can be reached through any other form of bridge-piece.

The frame of the sounding-box H' is composed of two ends and two sides, to wit: the bridge-piece B and the counter-piece B', and two pieces which form sides. The said bridge-piece and its counter-piece are grooved, lipped, and rear-beveled. These four pieces of wood, when properly joined, and the top and back pieces inserted into the said grooves and glued thereto and to the sides, form a sonorous box.

To give an arch form to the said sounding-box the side pieces are of curved form and give in the direction of the string-strain the form shown in Figure 2, the props d aiding in the maintenance of said form.

The strings, seventeen in number, are attached to the rear slopes of the said bridge and counter-bridge pieces B B' by pegs and the tuning-pins, and are caused to rest on the usual pillow-wires, and which have a decided improvement in tone effect when they are placed on the lips h, which to that end are extended forward upon the sounding-board.

The arrangement of the diatonic scale upon the said sounding-board, in connection with the frets shown and the tuning wedge-shaped block used therewith, renders the operation of tuning-adjustment of the strings more nearly a mechanical operation than any hitherto-applied method; and to obtain range for the tuning of the strings from the third string A to the ninth string G, forming the first octave, I place the frets on the left hand of the sounding-board, and move the tuning-wedge from fret to fret toward the right hand, which will be found to be in reverse to the operation attending the application of the same wedge-block in tuning another not greatly dissimilar instrument of my construction, which forms the subject of a contemporaneous application herewith.

In the accompanying drawings, in which similar letters indicate corresponding parts, Fig. 1 is a face or plan view, and Fig. 2 a cross-section from X to X on the said plan.

The sounding-board A will be seen to extend into the grooves E, which are formed in the inner faces of the bridge-piece B and counter-piece B' for its reception and support. The said pieces have rear-sloping bevels, which, with the depth of the said grooves E below their tops, gage the depth and form of the pillow'd bridges D D', in which are inserted the string-pegs c and the tuning-pins a for holding and straining the wires F.

The sound-hole C is for the common purpose of affording vent to the internal sounds of the sound-box. The left-hand position is shown of the frets b and the wedge-shaped tuning-block H.

h is an inward projection of the bridge and counter-bridge pieces, which forms lips, over which the said wire pillows D D' are laid, and which serve by their extension beyond the rigid inner walls of the end pieces to greatly enhance the tone of the instrument;

but this I do not in this application claim, as it is, with the overlapping lip *h*, the subject of a contemporaneous application. The props *d* form both a support to the sounding-board and an aid in preserving the curvature of the said sounding-box.

The diatonic scale I is attached as an aid toward the precise learning and tuning of the instrument and the music adapted to its compass.

To perform rightly the operation of tuning my instrument, tighten G, the second string, so as to sound G; then take the said tuning-wedge and place it between the first and second strings, D and G, at the top, with the broad side against the first string and the sharp edge resting on the first line under the second string, G, which will then, when struck, give the sound of A, the third string one tone higher, to which the said third string A is to be tuned in unison; then move the wedge to the next line and the second string G will give

the sound of B, to which tune the fourth string, said B, in unison likewise; then move the wedge to the third line and tune the fifth string, and so on until the first eight strings have been tuned, which completes the first octave. It is now very easy to proceed with the other strings, as it is simply tuning the remaining in octaves—thus, the tenth to the third, the eleventh to the fourth, &c.

Having described my invention, what I claim is—

A zithern having the high-arched bridge-piece B and the curved sound-box H' with the frets *b* and diatonic scale I, substantially as described, and for the purpose set forth.

In testimony that I claim the foregoing as my own invention I affix my signature in presence of two witnesses.

CHARLES KUNKEL.

Witnesses:
